DESIGN FOR A COVER FOR A SWITCH BOX OR THE LIKE

William H. Lantz, Jr., Minerva, Ohio, assignor to American Electric Switch Corporation,
Minerva, Ohio

Application July 1, 1937, Serial No. 70,193

Term of patent 3½ years

To all whom it may concern:

Be it known that I, William H. Lantz, Jr., a citizen of the United States, residing at Minerva, in the county of Stark and State of Ohio, have invented a new, original, and ornamental Design for a Cover for a Switch Box or the like, of which the following is a specification, reference being had to the accompanying drawing, forming part thereof, in which:

Fig. 1 is a plan view,

Fig. 2 is a side view, and

Figs. 3 and 4 are sectional views on lines 3—3 and 4—4 respectively of Fig. 1, of a cover for a switch box or the like, showing my new design.

I claim:

The ornamental design for a cover for a switch box or the like, as shown.

WILLIAM H. LANTZ, JR.
